UNITED STATES PATENT OFFICE.

DAVID ISHBIA, OF PALISADES, NEW JERSEY.

DISPLAY SIGN.

Application filed December 9, 1921. Serial No. 521,178.

To all whom it may concern:

Be it known that I, DAVID ISHBIA, a citizen of the United States, and resident of Palisades, New Jersey, have invented certain new and useful Improvements in Display Signs, of which the following is a specification.

This invention relates to illuminated display devices and particularly to an improved form of sign adapted to advertise a commodity to be sold and also arranged to signify the price of such commodity or to indicate or direct the attention to other matters concerning the commodity advertised. The sign is particularly designed for use in connection with the pump pedestals used at gasoline filling stations, garages or other establishments catering to the motoring public.

The device, however, is not limited to such use, as its character is such that it can readily be adapted to other uses as will be apparent from the following description.

One object of the invention is to provide an illuminated sign of durable construction which is comparatively inexpensive to manufacture. A further object is to provide a sign of neat appearance and adapted to readily attract the attention of passing motorists. A further object is to provide improvements in the design and details of construction of devices of this character so that they will readily withstand destructive action of the elements without materially weakening the structure or obliterating the advertising matter carried thereby. Other objects will be apparent from the following specification when read in connection with the accompanying drawings in which—

Fig. 1 is a front elevation with parts broken away to reveal the structural details;

Fig. 2 is a sectional view on the line 2—2 of Fig. 1;

Fig. 3 is a horizontal section on the line 3—3 of Fig. 1;

Fig. 4 is a detail section on the line 4—4 of Fig. 1.

In the drawings 2 represents a pedestal of any suitable construction which may be the upper end of a gasoline pump. To the cap 4 of this pedestal is secured the base 6 of my improved device which is of frustoconical formation and which comprises an outer shell 8 having a substantially horizontal flat top plate 10 and a cylindrical portion 12 which is seated on the cap 4 of the ped-

estal. Within the base 6 is located a frustoconical reinforcing member 14 which is soldered or otherwise secured to the interior of the base 6 near its lower end as at 16. The inclination of the reinforcement 14 is at a different angle than the outer shell 8 of said base and is secured to the top plate 10 by a soldered joint 18 near the central axis of the said top plate. Located above the top plate in juxtaposition to the soldered joint 18 is secured a lateral member 20 which carries at its outer ends uprights 22 and 24. These uprights are preferably of rectangular hollow cross-section and are formed with inner flanges 26 and 28. The uprights 22 and 24 together with the flanges 26 and 28 and a flange 21 formed on the lateral member 20, constitute a frame to which advertising signs 30 and 32 are secured by means of suitable screws 34.

The underside of the lateral member 20 is braced by tubular gusset members 36 which are soldered or otherwise secured to the exterior of the base 6. These gusset members firmly and rigidly support the member 20 and parts carried thereby and prevent the same from being dislodged by wind pressure or action of the elements.

The uprights 22 and 24 support a gabled hood 40 within which is located a single lamp adapted to illuminate the signs 30 and 32 which advertise the commodity to be sold and this lamp also illuminates a pair of transparent windows or signs carried by dormers extending outwardly from the gabled hood 40.

The gabled hood comprises end gables 42 and 44 which are secured by screws 46 and 48 to the uprights 22 and 24 respectively. These end gables are flanged over as indicated at 50 and 52 and are spot-welded or otherwise secured to the inclined roof portions 54 and 56 of the hood. At the lower end of each roof portion the hood is formed with substantially vertical overhanging portions 58 and 60 which are turned under at 62 and 64 forming a bead to present a neat finish. Openings 66 and 68 are formed in the roof portions 54 and 56 and are enclosed by extensions or dormers 70 and 72 which are provided with respectively top and side flanges 74 and 76 which are spot-welded or otherwise secured to the roof portions of the hood. The dormers are provided with windows or transparent signs 78 and 80. At the top of each dormer is flanged over as at

82, and adjacent thereto is secured a thin angle bar 84 forming a guide slot 86 for the transparent sign. A flange 88 is formed at the one end of each dormer forming a neat finish and adapted to cover one end of the detachable transparent sign. Located substantially in alignment with the flange 82 and secured to each roof portion 54 and 56 is an angular bar 90 having a vertical lip 10 92 and forming a seat or guide for the lower end of the transparent sign. The end wall 71, Fig. 4, of each dormer 70 and 72 is flanged outwardly as at 73 and provided with a cut away portion 75 so that said signs can be readily grasped by the thumb and forefinger to permit their removal.

To one of the uprights 22, for example, is secured a bracket 91 which carries a socket 93 in which is an incandescent lamp 94. 20 Current is supplied to the lamp by suitable electrical conductors 96 which extend outwardly through the hollow bracket 90, downwardly through the hollow upright 22 and laterally through the interior of the supporting member 20 through an insulating bushing 98 secured to the interior of the supporting base and projecting into the lateral member 20.

From the above description the utility of 30 the device will be readily appreciated. The signs 30 and 32 may be of opaque material and have delineated thereon suitable advertising matter descriptive of the commodity to be sold. For example, when this is used 35 in connection with gasoline pumps at filling stations or garages, the name of the manufacturer or his trade name may be delineated in suitable lettering and associated therewith may be displayed in bold characters 40 the words "Gas" or "Gasoline." The transparent signs are intended to signify the price per gallon at which the gasoline is sold. This price usually fluctuates from 45 time to time at different seasons of the year and the detachable transparent signs 78 and 80 can be readily removed and replaced by others according to fluctuations in the market price of the fuel.

In the inner sides of the roof portions 54 and 56 are either made of bright material 50 or are painted so as to readily reflect the light from the lamp 94 to the signs 30 and 32; and the light from said lamp will also shine through or illuminate the transparent signs 78 and 80 as will be understood. If desired the signs 30 and 32 can be separate plates as shown, or a single plate may be used having separate signs painted or otherwise depicted on the opposite faces thereof. 55 The signs may contain the advertising matter for the same product in which case the windows 78 and 80 will contain the same price characters or the signs may advertise different products, for example, gas and 60 oil, in which case the characters on the win-

dows 78 and 80 will be correspondingly chosen.

While I have described with great particularity of detail the embodiment of the invention herein shown, it is not to be construed that I am limited thereto as changes in construction and modifications may be made without departing from the invention as defined in the appended claims.

What I claim is:

1. A display sign comprising a base having uprights secured thereto, a hood carried by said uprights, a sign beneath said hood secured to said uprights and a single lamp within said hood adapted to illuminate said sign, the inner surface of said hood serving as a reflector to direct the rays of light to both sides of said sign.

2. A display sign comprising a base having uprights secured thereto, a hood carried by said uprights, a sign beneath said hood both sides of which are adapted to advertise a commodity, dormers secured to said hood and detachable signs slidably engaging guides on said dormers adapted to designate the price of the said commodity and a single lamp within said hood for illuminating all of said signs, said lamp being located centrally above the first named sign and arranged to illuminate both sides thereof.

3. A display sign comprising a frustoconical sheet metal base having an inner conical reinforcement, a lateral hollow sheet metal secured thereto carrying an upright at each end, reinforcing gusset brackets rigidly securing said member to said frustoconical base, ribs formed on said member and said uprights, and a sign secured to said ribs adapted to display an advertisement, a hood having slanting surfaces which intersect above said sign, dormers secured to said hood and transparent signs carried by said dormers and a lamp located within said hood and arranged to illuminate all of said signs.

4. In a display sign, a hood, signs carried by said hood, a single means for illuminating all of said signs, uprights secured to said hood, a lateral member for supporting said uprights, and a base having a horizontal top plate to which said lateral member is secured, said base being of shell-like formation having an outwardly and downwardly extending side wall and a reinforcing member within said base and secured at one end near the bottom of said base and at the other end to the underside of said horizontal top-plate in juxtaposition to said lateral member.

5. In a display sign, a hood, signs carried by said hood, a single means for illuminating all of said signs, uprights secured to said hood, a lateral member for supporting said uprights, and a base having a horizon-

tal top plate to which said lateral member is secured, said base being of shell-like formation having an outwardly and downwardly extending side wall and a reinforcing member within said base and secured at one end near the bottom of said base and at the other end to the underside of said horizontal top-plate in juxtaposition to said lateral member and reinforcing gusset members secured below said lateral member on opposite sides of said base to rigidly secure the lateral member to the base.

6. A display sign comprising a sheet metal hood having oppositely inclined roof portions, gable ends secured to said roof portions, dormers carried by said roof portions, transparent signs slidably secured in said dormers, hollow metallic uprights secured to said gable ends, a lateral member secured to said uprights, flanges formed on said uprights, a sign secured to said flanges, an electric lamp carried by one of said up-

rights adapted to illuminate all of said signs, a hollow metallic base to which said lateral member is secured and an electrical conductor enclosed by said base, said lateral member and one of said uprights for conveying current to said lamp. 25

7. An illuminated sign comprising a hollow frame, the wall thereof serving as an electric lamp wire conduit, a sign supported vertically in the frame, a roof having inclined sides, said roof being supported above the sign and upon the aforesaid frame and provided with side openings therein, a lamp carried by the frame and within the roof and opposite the aforesaid openings, and detachable auxiliary signs supported on the roof and opposite the aforesaid openings 35 40 therein.

In witness whereof, I have hereunto signed my name.

DAVID ISHBIA.
